UNITED STATES PATENT OFFICE.

JOHN EMERSON, OF TOLEDO, OHIO.

HEADWEAR.

Application filed October 3, 1925. Serial No. 60,195.

This invention relates to band size adjustable headwear.

This invention has utility when incorporated in loose or undress type of caps.

5 Referring to the drawings:

Fig. 1 is a view of the cap of the invention as in use;

10 Fig. 2 is a view of the cap with the front overhang pulled up to show the feature of the invention as incorporated therewith;

Fig. 3 is a plan view with the top of the cap broken away to show the band assembly features;

15 Fig. 4 is a view of the extension feature between the main band portions; and

Fig. 5 is a detail view of the spring extension hereunder.

The cap herein is shown as comprising a top 1 having a rear band portion 2, a front 20 band portion 3, from which forwardly extends a visor 4 carrying a snap element 5

with which may coact companion snap element 6 in overhang or loose slouch portion 7 of the hat top or body 1. Between the 25 rear band portion 2 and the front band portion 3, is slot or separation 8 in the outer material, while cap lining 9 carries at this joint, gusset 10. From the rear band portion sides, as adjacent these slots 8, extend

30 forwardly, strips or extensions 11 as extensible means each terminating in a snap element seat 12 with decorative backer or button mounting 13 therefor. Between these extensions 11, there is introduced herein

35 steel spring 14 having its helices or pitch flattened so that the product is in the form of a strap. This metallic spring strip 14 has loops 15 at each end thereof to carry companion snap elements 16, one for detachable

40 engagement with each of the snap element seats 12 of the extensions 11. There is, accordingly, completed in the overhang 7 and over the visor 4, a circuit about the front

band portion 3 by the rear band portion 2, the extensions 11 and the extensible section 45 14.

In the structure of this disclosure, there is thus provided a slightly exposed self-adjusting slack take-up band structure in the production of an article of headwear with 50

a wide range of comfort adaptation in size. The cap as pulled into position is for a range of sizes, a snug but not objectionable fit. It is thus comfortably held against accident or

55 wind removal. The fit is slightly. The assembly is detachable and one which may be readily incorporated in the article of headwear. This feature has great commercial

value in addition to the comfort and value to the wearer in that the merchant need 60 not be compelled to stock sizes, but merely styles, and the size will accommodate the trade automatically due to the invention hereunder.

What is claimed and it is desired to secure by United States Letters Patent is:

1. The combination for an article of headwear of an adjustable head-band comprising a main section and a pair of straps oppositely extending therefrom to provide a 70

pair of free ends, a flat ribbon coil spring between the free ends of said straps, and snap terminals for the spring for disconectably anchoring the spring to the free ends of the straps in thus completing a head- 75

2. An adjustable head-band extensible section as an article of manufacture comprising a flat ribbon spring having terminals and snap connecting devices coacting with 80 said terminals for attachably assembling said spring as a head-band extensible section in a head-band.

In witness whereof I affix my signature.

JOHN EMERSON.
